UNITED STATES PATENT OFFICE.

HERBERT M. DARMSTADTER, OF PITTSBURGH, PENNSYLVANIA.

HAT-CREASER.

1,335,486.

Specification of Letters Patent. Patented Mar. 30, 1920.

Application filed December 5, 1919. Serial No. 342,596.

To all whom it may concern:

Be it known that I, HERBERT M. DARMSTADTER, a citizen of the United States, residing at Pittsburgh, in the county of Allegheny and State of Pennsylvania, have invented new and useful Improvements in Hat-Creasers, of which the following is a specification.

This invention relates to a device for holding the crease in felt hats and the principal object of the invention is to provide means for causing the device to firmly grip the creased part of the hat and thus prevent the device from dropping out of the hat.

Another object of the invention is to provide the device with wide side portions so that advertising material may be placed thereon.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:

Figure 1 is a view showing the device placed in the hat.

Fig. 2 is a perspective view of the device.

Fig. 3 is a cross sectional view.

As shown in the drawing the device is formed of a strip of suitable material, preferably of metal, which is looped upon itself to form the two jaws 1 and 2. The folded over part is cut away at each end, as at 3, to provide the inclined parts. The edges of the jaws at their ends are bent inwardly to provide the beveled edges 4 so as to insure the jaws gripping the hat and thus preventing the device from slipping or falling out. These beveled parts may extend up the inclined parts as shown in the drawing. It will be seen that the jaws are of considerable width so that advertising material may be placed thereon.

The device is adapted to be placed in the hat with its jaws gripping the longitudinal crease therein as shown in Fig. 1 so as to hold the hat in proper shape.

It is thought from the foregoing description that the advantages and novel features of my invention will be readily apparent.

I desire it to be understood that I may make changes in the construction and in the combination and arrangement of the several parts provided that such changes fall within the scope of the appended claim.

What I claim is:—

A device of the class described comprising a strip bent upon itself to provide a pair of jaws with the edges of the jaws bent inwardly to provide beveled gripping edges.

In testimony whereof I affix my signature.

HERBERT M. DARMSTADTER.
